CLAIM

I claim the ornamental design for a railing support bracket, as shown and described.

DESCRIPTION

Reference is made to Design application Ser. No. 29/395,835 filed Apr. 6, 2012 which depicts a Mounting Bracket having a tubular upstanding stem that can be used with the bracket of the present invention.

FIG. 1 is a perspective view showing front, top and right side features of a first embodiment of my design;

FIG. 2 is a front elevational view thereof;

FIG. 3 is a top plan view thereof;

FIG. 4 is a bottom plan view thereof;

FIG. 5 is a right side elevation view thereof, it being understood that a left side elevation view is identical hereto; and, FIG. 6 is a perspective view showing front, top and right side features of a second embodiment of my design.

The broken lines showing holes are for the purposes of illustrating environment and form no part of the claimed design.
